[57] **CLAIM**

The ornamental design for a “key layout for a telephone headset”, as shown and described.

DESCRIPTION

FIG. 1 is a top, front, left side perspective view of a key layout for a telephone handset showing my new design; FIG. 2 is a front elevational view thereof; and, FIG. 3 is a bottom, front, right side perspective view thereof. The dotted lines showing the outline of a telephone handset is for illustration purposes only and forms no part of the claimed invention.
